BOTTLE CLOSURE APPLYING DEVICE

Filed Sept. 20, 1922

REVERE: Sigmund J. Goldman,
By Doranforth, Lee, Chittory, Wills,
Attys.

UNITED STATES PATENT OFFICE.

SIGMUND L. GOLDMAN, OF CHICAGO, ILLINOIS.

BOTTLE-CLOSURE-APPLYING DEVICE.

Application filed September 20, 1922. Serial No. 589,362.

To all whom it may concern:

Be it known that I, SIGMUND L. GOLDMAN, a citizen of the United States, residing at Chicago, in the county of Cook and State 5 of Illinois, have invented a new and useful Improvement in Bottle-Closure-Applying Devices, of which the following is a specification.

My invention relates generally to bottle-10 closure-applying devices as, for example, for applying caps to bottles, though it is not limited thereto.

My primary object is to provide a simplified construction of device of the character 15 above stated which may be manufactured economically, and will operate to a high degree of satisfaction.

Referring to the accompanying drawing:

Figure 1 is a view in side elevation of a 20 capping device constructed in accordance with my invention. Figure 2 is a similar view of the device viewing it from the right hand side of Fig. 1; and Figure 3, a section taken at the line 3—3 on Fig. 1 and viewed 25 in the direction of the arrows.

The particular illustrated embodiment of my invention involves a base member, represented at 4, which is preferably formed of sheet metal to afford the plate-like section 30 5 at which the device is adapted to bear upon the support to which the capper would be applied, the plate portion 5 being provided at one edge with an upstanding rib 6 and at its edges angularly disposed thereto, 35 with upwardly-extending side portions 7 having flanges 8 which extend directly above the rib 6, the portions 6 and 7 cooperating with each other to provide a durable construction of base. The device also comprises an upright represented generally at 40 9 and provided along its inner edge with teeth 10 constituting a rack. The upright 9 is shown as formed of a pair of similar bars 11 presenting at their upper ends the flat 45 portions 12 which flatwise oppose each other and at which the bars are secured together as through the medium of the rivets 13, the teeth 10 being formed in the edges of the double bar construction thus provided. Be- 50 low the flattened portions 12, the bars 11 di- 55 verge outwardly at the portions indicated at 14, their lower extremities, represented at 15, being substantially parallel and located within the space between the side por- 60 tions 7—7 which latter they flatwise oppose

as shown. The upright 9 is shown as riveted, at the lower extremities of its portions 15, to the side member 7, as represented at 16, which may afford a pivotal mounting for the upright 9 if desired, and is rigidly secured to the side members, at points above the rivets 16, as by bolt devices 17. It may be here stated that the particular construction of the base plate, the upright and the means connecting these parts together, are 60 not material to my present invention. The device also involves a slide, represented at 18, which cooperates with the rack portion 10 of the upright, and in the particular construction shown is formed of a U-shaped 65 member bent from a single sheet of metal to present the side walls 19 and a rear connecting wall 20. Each of the side walls 19, between its lateral edges, is deflected inwardly, 70 as represented at 21, thereby affording a channel, represented at 22, into which the rack portion 10 of the upright 9 extends and on which latter the slide 18 is vertically movable. The deflection of the side walls 75 at 21 causes the channel 22 to present guide 80 surfaces opposing all four sides of the rack portion 10 of the bar, thereby restraining the slide from rocking movement thereon in all directions.

The rack 10 cooperates with a gear segment, represented at 23, which is shown as carried on the end of a hand-operated lever 24, this gear segment being located between the side walls 19 and pivotally connected therewith, as through the means of the pivot 85 represented at 25 and which may be a rivet or any other suitable pivoting means, the teeth of the segment 23 meshing with the rack 10. In this connection it may be stated that the parts described are so constructed and arranged that by swinging the lever 24 in clockwise direction to a certain position from that shown in Fig. 1, the teeth of the segment 23 will be out of mesh with the rack 90 10, permitting the slide 18 to be ad- 100 justed on the rack to any desired position, or removed therefrom if desired.

The slide 18 is provided with a bottle- 105 closure-engaging portion provided, in the particular arrangement shown, for receiving a metal cap to be applied and secured to the mouth of a bottle. In the construction shown this portion is formed of a separate inverted cup-shaped member 26 with the lower edges of its wall flaring outwardly, 110

The member 26 bears at its upper, closed, end, flatwise against laterally-extending lugs 27 shown as formed integrally with the side walls 19, and is rigidly secured thereto as by means of rivets, represented at 28, passing through these lugs and the base portion of the member 26.

It will be understood from the foregoing that by swinging the lever 24 in counter-clockwise direction in Fig. 1, the slide 18 will be forced downwardly for effecting the bottle-closing operation, the feature of so forming the parts that the teeth of the segment 23 may be swung out of engagement with the teeth of the rack 10, adapting the device for the most efficient operation in connection with bottles of widely varying heights.

The thickness of the gear segment 23 is less than the thickness of the rack portion 10, whereby the gear segment is adapted to be located within the space afforded between those portions of the walls 19 which are most closely spaced apart. The deflected portions of the walls 19, partially overlap the front faces of the teeth of the rack 10 thereby forming guides for the segment 23.

It will be noted that by constructing the slide as shown and above described, the minimum number of fastening devices is required, which reduces to the minimum the cost of producing the device, while causing the latter to present the desired strength and the desired functioning.

Another feature of the construction described is that of so proportioning the various parts thereof that regardless of the position to which the slide 18 may be depressed on the upright, the slide will not become wedged thereupon, as the lower edge of the slide 18 does not, in any position thereof while the gear segment 23 is in mesh with the rack 10, lower to the point where the deflected portions 14 join the flat portions 11.

While I have illustrated and described a particular construction embodying my invention, I do not wish to be understood as intending to limit it thereto as the same may be variously modified and altered without departing from the spirit of my invention.

What I claim as new, and desire to secure by Letters Patent, is:

1. In a bottle-closure-applying device, the combination of a rack-bar, a slide on said bar and provided with a bottle-closure-engaging part, and a toothed member pivoted on said slide and engaging the teeth of said bar, said slide being formed with side walls spaced apart and an end wall connecting said side walls at one end of said slide and at its end-wall portion straddling said rack-bar, said side-walls being deflected inwardly between their lateral edges to form

a guide channel in which said bar extends, said toothed member being located between said side walls with its toothed portion of less thickness than the thickest portion of said rack-bar, said deflected portions being located at opposite sides of said toothed member and flatwise opposing the opposite sides of the latter and also opposing the face of the teeth thereon.

2. In a bottle-closure-applying device, the combination of a rack-bar, a slide on said bar and provided with a bottle-closure-engaging part, and a toothed member pivoted on said slide and engaging the teeth of said bar, said slide being formed with side-walls so spaced apart and an end wall connecting said side-walls at one end of said slide, and at its end-wall portion straddling said rack-bar, said side-walls being deflected inwardly between their lateral edges substantially throughout their height to form a guide channel in which said bar extends, said side walls at their points of deflection extending opposite the face of the teeth of said rack-bar, and said toothed member being located between said side-walls with its toothed portion of less thickness than the thickest portion of said rack bar.

3. In a bottle-closure-applying device, the combination of a rack-bar, a slide on said bar and provided with a bottle-closure-engaging part, and a toothed member pivoted on said slide and engaging the teeth of said bar, said slide being formed with side-walls spaced apart and an end wall connecting said side-walls at one end of said slide, and at its end-wall portion straddling said rack-bar, said side-walls being deflected inwardly between their lateral edges substantially throughout their height to form a guide channel in which said bar extends, said side walls at their points of deflection extending opposite the face of the teeth of said rack-bar, the side-walls at the opposite edge of said slide being spaced closer together, and said toothed member being of less thickness than said rack-bar and located between said last-referred-to portions of said side-walls.

4. In a bottle-closure-applying device, the combination of a rack-bar, a slide on said bar and provided with a bottle-closure-engaging part, and a toothed member pivoted on said slide and engaging the teeth of said bar, said slide being formed with side-walls spaced apart and an end wall connecting said side-walls at one end of said slide, and at its end-wall portion straddling said rack-bar, said side-walls being deflected inwardly between their lateral edges substantially throughout their height to form a guide channel in which said bar extends, said side walls at their points of deflection extending opposite the face of the teeth of said rack-bar and said toothed member being located

between said side-walls with its toothed portion of less thickness than the thickest portion of said rack-bar, said pivoting means having portions preventing said side-walls 5 from spreading.

5. In a bottle-closure-applying device, the combination of a rack-bar, a slide on said bar and provided with a bottle-closure-engaging part, a toothed member pivoted 10 on said slide and engaging the teeth of said bar, said slide being formed with side-walls spaced apart and an end wall connecting said side-walls at one end of said slide, and at its end-wall portion straddling said rack-bar, said side-walls being deflected inwardly between their lateral edges to form a guide channel in which said bar extends, and said toothed member being located between said side-walls with its 15 toothed portion of less thickness than the thickest portion of said rack-bar, said deflected portions being located at opposite sides of said toothed member and flatwise opposing the opposite sides of the latter and 20 also opposing the face of the teeth thereon, said pivoting means having portions preventing said side-walls from spreading, said bottle-closure-engaging part being separate from said side-walls, and means connecting 25 said part to said side-walls and preventing spreading of the latter.
6. In a bottle-closure-applying device, the combination of a rack-bar, a slide on said bar and provided with a bottle-closure-engaging part, a toothed member pivoted on 30 said slide and engaging the teeth of said bar, said slide being formed with side-walls spaced apart and an end wall connecting said side-walls at one end of said slide, and at its end-wall portion straddling said rack-bar, said side-walls being deflected inwardly between their lateral edges substantially throughout their height to form a guide channel in which said bar extends, said side walls at their points of deflection 35 extending opposite the face of the teeth of said rack-bar, and said pivoting means having portions preventing said side walls from spreading, said bottle-closure-engaging part 40 being separate from said side walls, and means connecting said part to said side walls and preventing spreading of the latter.
7. In a bottle-closure-applying device, the combination of a rack-bar, a slide on said bar provided with laterally-extending lugs, a bottle-closure-engaging member bearing against said lugs, means engaging said lugs and member for fastening said member to said lugs, and a toothed member pivoted on said slide above said first-named member and engaging the teeth of said bar, said slide being formed with side-walls spaced apart and an end wall connecting said side-walls at one end of said slide, and at its end-wall portion straddling said rack-bar, said side-walls being deflected inwardly between their lateral edges to form a guide channel in which said bar extends, and said toothed member being located between said side-walls with its toothed portion of less thickness than the thickest portion of said rack-bar, said deflected portions being located at opposite sides of said toothed member and flatwise opposing the opposite sides of the latter and also opposing the face of the teeth thereon.
8. In a bottle-closure-applying device, the combination of a rack-bar, a slide on said bar provided with laterally-extending lugs, a bottle-closure-engaging member bearing against said lugs, means engaging said lugs and member for fastening said member to said lugs, and a toothed member pivoted on said slide above said first-named member and engaging the teeth of said bar, said slide being formed with side-walls spaced apart and an end wall connecting said side-walls at one end of said slide, and at its end-wall portion straddling said rack-bar, said side-walls being deflected inwardly between their lateral edges substantially throughout their height to form a guide channel in which said bar extends, said side walls at their points of deflection extending opposite the face of the teeth of said rack-bar, and said toothed member being located between said side walls with its toothed portion of less thickness than the thickest portion of said rack-bar.
